CLAIM

The ornamental design for a pill box, as shown and as described.

DESCRIPTION

FIG. 1 is a front-top perspective view of the pill box showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side view thereof;

FIG. 7 is a left side view thereof;

FIG. 8 is a front-top perspective view of the pill box in an open configuration; and,

FIG. 9 is a front-top perspective view of the pill box in an open configuration with divided compartments therein.

The broken lines in the FIGURES represent a portion of the pill case that forms no part of the claimed design.

1 Claim, 9 Drawing Sheets
